US00D589144S

(12) **United States Design Patent**
Bagha et al.

(10) **Patent No.:** **US D589,144 S**
(45) **Date of Patent:** **** Mar. 24, 2009**

(54) **MEDICAL DEVICE**

(76) Inventors: **Merat Bagha**, 7971 NW. Blue Pointe La., Portland, OR (US) 97229; **Kim Porter Henneman**, 1914 NE. 50th Ave., Portland, OR (US) 97213; **I-Chiang Sun**, 3808 SW. Troy St., Portland, OR (US) 97219

(**) Term: **14 Years**

(21) Appl. No.: **29/273,940**

(22) Filed: **Mar. 15, 2007**

(51) LOC (9) Cl. **24-02**

(52) U.S. Cl. **D24/134**

(58) **Field of Classification Search** D24/134; 181/131-132, 136-167, 133, 67; 600/454, 600/453, 500, 527-528

See application file for complete search history.

(57) **CLAIM**

The ornamental design for a medical device, as shown and described.

DESCRIPTION

FIG. 1 is an isometric view of a medical device showing our new design;

FIG. 2 is a top view thereof;

FIG. 3 is a bottom view thereof;

FIG. 4 is a left side view thereof;

FIG. 5 is a right side view thereof;

FIG. 6 is a front end view thereof;

FIG. 7 is a rear end view thereof; and,

FIG. 8 is an isometric view of the medical device of FIG. 1 showing a tube portion in an alternate position.

Elements illustrated in the drawing figures using broken lines illustrate intended environmental components and do not constitute part of the claimed design.

1 Claim, 3 Drawing Sheets
